UNITED STATES PATENT OFFICE.

JOHN W. BALDWIN, OF GRAND RAPIDS, MICHIGAN.

BUTTON-REMOVER.

1,291,364.

Specification of Letters Patent. Patented Jan. 14, 1919.

Application filed December 28, 1917. Serial No. 209,237.

To all whom it may concern:

Be it known that I, JOHN W. BALDWIN, a citizen of the United States, residing at Grand Rapids, county of Kent, State of Michigan, have invented certain new and useful Improvements in Button-Removers, of which the following is a specification.

This invention relates to improvements in button removers.

10 My improved button remover is, in the embodiment illustrated, especially designed by me for removing sewed shoe buttons, although my improvements are desirable for embodiment in structures adapted for removing other types of buttons.

15 The main object of the invention is to provide an improved button remover for sewed buttons by means of which the buttons may be quickly removed without injury to the button, or to the fabric, or leather upon which it is sewed.

20 Further objects, and objects relating to structural details, will definitely appear from the detailed description to follow.

25 I accomplish the objects of my invention by the devices and means described in the following specification. The invention is clearly defined and pointed out in the claims.

30 A structure which is a preferred embodiment of my invention is clearly illustrated in the accompanying drawing, forming a part of this specification, in which:

35 Figure I is a side view of a structure embodying the features of my invention.

Fig. II is a longitudinal section thereof on a line corresponding to line 2—2 of Fig. III.

Fig. III is a detail bottom view.

Fig. IV is a detail section on a line corresponding to line 4—4 of Figs. I and II.

Fig. V is a front end view showing the jaws engaged upon a button preparatory to removing the same.

Fig. VI is an end view with the jaws partially open and the thread severing knife partially advanced.

Fig. VII is a similar view with the jaws farther advanced and the thread severed.

In the drawing similar reference characters refer to similar parts throughout the several views, and the sectional views are

taken looking in the direction of the little arrows at the ends of the section lines.

Referring to the drawing, I provide a pair of jaws 1 and 2 having handles 3 and 4, respectively. The jaws and handles are, in practice, preferably sheet metal stampings. The lower jaw 1 is provided with upwardly projecting side flanges 5, while the upper jaw 2 is provided with downwardly projecting side flanges 6 disposed between the flanges of the lower jaw. The jaws are pivotally connected by means of the pivots 7 formed by striking in parts of the flanges of the lower jaw, the pivots engaging pivot openings 8 in the upper jaw.

The handles are preferably channel-shaped in cross section, as illustrated. The flange portions of the handles are continuations or extensions of the flanges on the sides of the jaw. The lower jaw is provided with a T-shaped slot 9 adapted to receive the attaching thread of a button or the shank of a button and its attaching thread.

The side flanges of the upper jaw have inturned button engaging portions 10, the edges of which are spaced to form a slot 11 adapted to receive the eye of a button or the thread of a button, as the case may be.

A knife 12 having an upwardly beveled A-shaped cutting edge 13 is slidably mounted on the lower jaw between its side flanges. Lugs 14 are struck in from the side flanges of the lower jaw to slidably retain the blade. The blade has notches 15 in its edges which are engaged by the downwardly projecting lugs 16 on the side flanges of the upper jaw so that when the jaws are separated the knife is actuated across the slot 9, severing the thread which is drawn up through the slot by the separation of the jaws, as shown in Figs. VI and VII.

To collect the severed buttons I provide a closure plate 17 for the open inner side of the upper handle, the forward end of the plate being engaged with the rear end of the button engaging member of the upper jaw, while the rear end of the plate is secured within the handle by the rivet 17'. By holding the implement in an inclined position when severing buttons the buttons will drop into this holder which is adapted

to receive several of them. The buttons may be discharged merely by tilting the implement forwardly. The jaws are held in their closed position by means of the coiled 5 spring 18, the rear end of which is secured to a tongue 19 struck up from the handle 3, while the forward end is engaged with the end of a bar 20 one end of which is slideable within the handle 3 and the other end of 10 which is engaged with a lug 21 on the upper handle.

My improved button remover is well adapted for the removing of sewed buttons from shoes and the like, the same being 15 capable of very rapid manipulation. The attaching threads of the buttons are severed without injury to the fabric or leather to which they are attached.

I have illustrated and described my improved button remover as I have embodied 20 the same for removing shoe buttons. I have not attempted to illustrate or describe certain modifications and adaptations which might be desirable for removing other styles 25 of buttons, as it would be largely a matter of changing the design of the implement to accommodate the different sizes and styles of buttons.

Having thus described my invention, what 30 I claim as new and desire to secure by Letters Patent, is:

1. In a structure of the class described, the combination of a pair of slotted jaws, the lower jaw having upwardly projecting 35 side flanges between which the upper jaw is disposed, the upper jaw having downwardly projecting side flanges with inturned button engaging members spaced to form the shank slot of the upper jaw, the lower jaw having 40 pivots struck in from its side flanges engaging pivot openings in the side flanges of the upper jaw, said jaws being provided with handles, and the upper jaw handle being channel-shaped in cross section, a knife slidably mounted on the lower jaw and having 45 an A-shaped upwardly beveled cutting edge, the lower jaw having retaining lugs under which said blade reciprocates struck in therefrom, and said upper jaw having lugs 50 on its side flanges engaging said blade whereby it is reciprocated by the rocking of the jaws on their pivot, and a member disposed to coact with the upper handle to provide a button holder, the front end of 55 said member being engaged with the rear edges of the button engaging members of the upper jaw, and its rear end being secured to the upper jaw handle.

2. In a structure of the class described, 60 the combination of a pair of slotted jaws, the lower jaw having upwardly projecting side flanges between which the upper jaw is disposed, the upper jaw having downwardly projecting side flanges with inturned button 65 engaging members spaced to form the shank

slot of the upper jaw, the lower jaw having pivots struck in from its side flanges engaging pivot openings in the side flanges of the upper jaw, and said jaws being provided with handles, and a knife slidably mounted 70 on the lower jaw and having an A-shaped upwardly beveled cutting edge, the lower jaw having retaining lugs under which said blade reciprocates struck in therefrom, and said upper jaw having lugs on its side flanges 75 engaging said blade whereby it is reciprocated by the rocking of the jaws on their pivot.

3. In a structure of the class described, the combination of a pair of pivoted jaws 80 slotted to receive the shank of a button, the lower jaw having upwardly projecting side flanges between which the upper jaw is disposed, the upper jaw having downwardly projecting side flanges with inturned button 85 engaging members spaced to form the shank slot of the upper jaw, said jaws being provided with handles, and the upper handle being channel-shaped in cross section, a knife slidably mounted on the lower jaw, 90 means for actuating said knife when the jaws are separated, and a member disposed to coact with the upper handle to provide a button holder, the front end of said member being engaged with the rear edges of 95 the button engaging members of the upper jaw, and its rear end being secured to the upper jaw handle.

4. In a structure of the class described, 100 the combination of a pair of jaws slotted to receive the shank of a button and its attaching thread, said jaws having side flanges disposed one within the other, the flanges of one jaw having pivots struck therefrom engaging pivot openings in the 105 flanges of the other jaw, said jaws being provided with handles, and the upper jaw handle being channel-shaped in cross section, a knife slidably mounted on the lower jaw, means for actuating said knife on the separating of the jaws, and a closure member 110 for the open side of the upper handle to provide a button holder, the front end of the closure member being disposed between the flanges of the upper jaw. 115

5. In a structure of the class described, the combination of a pair of jaws movable toward and from each other, the lower jaw having a T-shaped slot adapted to receive the thread of a button, and the upper jaw 120 being adapted to engage a button, a knife slidably mounted on the lower jaw and having an A-shaped upwardly beveled cutting edge, and means for actuating said knife when the jaws are separated, the upper jaw 125 being provided with a handle adapted as a button holder.

6. In a structure of the class described, the combination of a pair of jaws movable toward and from each other, the lower jaw 130

having a T-shaped slot adapted to receive the thread of a button, and the upper jaw being adapted to engage a button, a knife slidably mounted on the lower jaw and having an A-shaped upwardly beveled cutting edge, and means for actuating said knife when the jaws are separated.

In witness whereof, I have hereunto set my hand and seal in the presence of two witnesses.

JOHN W. BALDWIN. [L. s.]
